US0D1099406S

(12) **United States Design Patent** (10) Patent No.: **US D1,099,406 S**
(45) Date of Patent: ** Oct. 21, 2025

(54) **LUMINAIRE**

(71) Applicant: **Lumenture, Inc.**, Monroe, CT (US)

(72) Inventors: **Kyle Rutkunas**, Monroe, CT (US);
James Leahy, Monroe, CT (US);
Nicholas P. Convertito, Monroe, CT (US)

(73) Assignee: **Lumenture, Inc.**, Monroe, CT (US)

(**) Term: **15 Years**

(21) Appl. No.: **29/880,044**

(22) Filed: **Jul. 17, 2023**

(51) LOC (15) Cl. **26-05**

(52) U.S. Cl.

USPC **D26/63**

(58) **Field of Classification Search**

USPC D26/1, 24, 25, 37, 40-45, 48, 50, 60, 61, D26/63, 93, 94, 102-112, 118, 128, D26/130-135, 138, 142; D9/414, 432; D16/208, 209, 219, 237, 241, 250

(74) Attorney, Agent, or Firm — DeWitt LLP; Brian R. Pollack, Esq.

(57) **CLAIM**

The ornamental design for a luminaire as shown and described.

DESCRIPTION

FIG. 1 is a top isometric view for the luminaire;

FIG. 2 is a front view thereof;

FIG. 3 is a back view thereof;

FIG. 4 is a right-side view thereof;

FIG. 5 is a left-side view thereof;

FIG. 6 is a top view thereof;

FIG. 7 is a bottom view thereof; and,

FIG. 8 is a top isometric view thereof showing relative placement of a lighting track adapter.

The broken lines are included for the purpose of illustrating the portions of the lighting track adapter that form no part of the claimed design.

1 Claim, 5 Drawing Sheets
